MANUFACTURE OF APPLICATORS

John F. Skold, Chicago, Ill., assignor to Charles E. Zimmerman, Chicago, Ill.

Original application October 26, 1939, Serial No. 301,343. Divided and this application June 3, 1940, Serial No. 338,669

9 Claims. (Cl. 164—17)

The present invention relates generally to the manufacture of pad-like applicators. More particularly the invention relates to the manufacture of that type of applicator which is formed of elastic material such as porous rubber latex and has a pocket forming slit leading into its interior from the side or periphery and adapted to be charged with the material to be applied in connection with the use of the applicator.

10 One object of the invention is to provide a simple and novel method of manufacturing an applicator of the aforementioned type which comprehends the formation in the applicator of a pocket forming slit with a restricted side entrance.

Another object of the invention is to provide a method of applicator manufacture which comprises as steps, first stretching one side of the applicator, then forming a semi-circular slit in 20 and beyond the stretched portion and finally releasing the applicator so that it assumes its normal shape and has the desired restricted entrance pocket forming slit therein.

A further object of the invention is to provide 25 a method which has particular utility in connection with the manufacture of a cosmetic applicator of the type which is disclosed in, and forms the subject matter of, United States reissue Letters Patent No. 21,399, issued on March 12, 1940, to Charles E. Zimmerman and entitled "Application of cosmetics."

Other objects of the invention and the various 30 advantages and characteristics of the present method of applicator manufacture will be apparent from a consideration of the following detailed description.

The invention consists in the improved method 35 which is hereinafter set forth and is more particularly defined by claims at the conclusion hereof.

In the drawings which accompany and form a 40 part of this specification or disclosure and in which like numerals of reference denote corresponding parts throughout the several views:

45 Figure 1 is a perspective view showing a pad-like applicator before it has been subjected to the improved method of manufacture for the purpose of forming in it a pocket forming slit with a restricted entrance;

50 Figure 2 is a plan view of an apparatus for carrying out the method;

Figure 3 is a vertical transverse section on the line 3—3 of Figure 2;

55 Figure 4 is a fragmentary plan view of the apparatus, illustrating the manner in which the

applicator is slit while in a stretched condition; Figure 5 is a vertical transverse section on the line 5—5 of Figure 4; and

Figure 6 is a perspective view showing the applicator after it has been slit for pocket forming purposes in accordance with the improved method.

The method which forms the subject matter of the invention comprehends the formation in a pad-like applicator 7 of a pocket forming slit 8 10 with a restricted entrance 9. The applicator 7 which is shown in the drawings is in the form of a disc or cylindrical pad and is formed of porous latex rubber. The slit 8 which is formed in the applicator serves as a pocket for the material to be applied by way of the applicator. It is substantially circular and is disposed concentrically with respect to the cylindrical side of the applicator. The entrance 9 of the slit intersects a portion of the cylindrical side or periphery of 20 the applicator and permits the pocket which is formed by the slit 8 to be filled or charged with the material to be applied. If the applicator is used for applying cosmetic powder the restricted entrance 9 permits a charge of powder to be 25 inserted into the slit. When the slit is charged with pulverulent material, such as powder, such material percolates through the pores in the body of the applicator and hence may be applied by patting the applicator against the surface to be 30 covered with the material. Whereas a disc-like or cylindrical applicator is shown in the drawings it is to be understood that the improved method is capable of being employed in connection with elastic applicators of other shape or 35 contour. The method comprises as its steps, first moistening the applicator with water, then gripping the applicator at the sides thereof, then stretching it to an appreciable extent, then forming in and beyond the stretched portion a semi-40 cylindrical slit and finally releasing the applicator so that it assumes its original shape. When the applicator is released after slitting the slit 45 therein has the desired restricted entrance. The applicator is preferably moistened with water by immersing in a body of water and then squeezing it. After removal from the body of water the applicator is squeezed so as to discharge all free water from it. The purpose of moistening the applicator prior to slitting is to make it easier to slit the article while it is in a stretched condition. The moistening step is of particular advantage when the applicator is formed of porous rubber latex. When the applicator is disc-like or cylindrical, as shown in the drawings, it is pref-

erably gripped at the end portions of a cordal line disposed midway between the center of the pad and the pad periphery and it is stretched until it assumes a crescent shape or semi-cylindrical condition. While the applicator is in such condition it is provided with the semi-cylindrical slit. Slitting is preferably accomplished by way of a circular rotary knife. When such a knife is employed the stretched portion of the applicator is moved toward the knife until the knife penetrates through the stretched side portion and enters the interior of the applicator to the desired extent. When the applicator is released after slitting it resumes its normal shape and, as previously pointed out, has a restricted slit entrance in its side portion.

Preferably the improved method of slitting is carried out in an apparatus like that shown in Figures 2 to 5 of the drawings. Such apparatus comprises a flat rectangular base plate 10, a rotary circular knife 11 and a unit 12 for stretching the applicator and moving it into engagement with the knife for slitting purposes. The base plate is supported in any suitable manner 25 and has in the central portion thereof a circular opening 13 through which the applicator after slitting may be dropped. The knife 11 is located at the other end of the base plate and is disposed in a horizontal position a slight distance above the plate. It is provided with a depending drive shaft 14 and this extends through a hole in the base plate and is coupled to the armature shaft of an electric motor (not shown). The unit 12 comprises a support 15 and a pair of grippers 16. 30 The support has an arcuate recess 17 in the upper front portion thereof for accommodating a portion of the applicator. It is disposed above, and extends transversely of, the base plate 10 at substantially the same elevation as the knife 11. 35 As shown in the drawings the support is mounted on the central portion of a horizontally extending rod 18 which is carried by a slide block 19 and a slide rod 20 so that it is shiftable laterally to and from the knife 11. The slide block 19 is fixedly secured to one end of the rod 18 and is slidably mounted on the rod 20. The latter overlies one side of the base plate and extends longitudinally of the latter. Brackets 21 extend between the base plate and the ends of the slide rod 20 and serve to hold the slide rod in a fixed position with respect to the base plate. Because of the rod 18, the slide block 19 and the slide rod 20 the applicator support 15 is mounted so that it is movable horizontally to and from the rotary knife 11. The grippers 16 are positioned in straddled relation with the applicator support 15 and are mounted on the rod 18 so that they are movable with the support to and from the knife in a horizontal plane. They are 40 adapted to grip the applicator at the sides thereof and serve to stretch the applicator as the latter is shifted toward and into engagement with the knife 11. Each of the grippers 16 consists of a lower member 22 and an upper member 23. 45 The lower members of the grippers have aligned sleeve-like parts 24 on the under side thereof and these parts are slidably mounted on the rod 18 and together with the rod support the grippers so that they are movable or slidable to and from one another. The front inner corners of the lower members 22 of the grippers are extended inwardly, as shown in Figure 2. They are adapted to underlie the side portions of the applicator when the latter is supported or carried by the support 15 and are connected to the ends of the

support by means of pivoted links 25. The upper members 23 of the grippers overlie the front portions of the lower members and are horizontally elongated. They extend transversely of the base plate 10 and are centrally fulcrumed or pivoted by way of pivot pins 26 which are carried by pairs of upstanding ears 27 on the front portions of the lower members 22 of the grippers. The inner ends of the upper members 23 overlie the inwardly extended inner front corners of the lower members (see Figure 5). Vertically extending compression springs 28 extend between the lower gripper members and the outer ends of the upper gripper members and operate to urge the upper members into clamped relation with the applicator. When the grippers are in clamped 20 relation with the applicator and are shifted apart the applicator is caused to stretch, as shown in Figure 4. For the purpose of moving the grippers apart and effecting stretching of the applicator in connection with shifting of the applicator toward the rotary knife 11 two horizontally extending rods 29 are provided. These rods are suitably supported above, and extend substantially longitudinally of, the base plate 10 and are divergent in the direction of the knife 11. The lower members of the grippers are provided on the top portions thereof with sleeve-like parts 30 and these are slidably mounted on the rods. Because of the fact that the rods diverge in the direction of the knife 11 the grippers are caused to separate 35 and effect stretching of the applicator when the latter is carried by the support and the grippers and is moved toward and into engagement with the knife 11. The grippers are so arranged that the applicator when carried thereby is horizontally aligned with the knife 11. A handle 31 is applied to the lower member of one of the grippers and is adapted to be used in connection with shift of the grippers and support to and from the knife. The links 25 serve to hold the support 40 45 in centered relation with the grippers during sliding movement of the grippers on the divergent rods 29. For the purpose of automatically swinging the upper members of the grippers out of clamped relation with the applicator at the end 50 of the retractile stroke of the grippers the upper members are provided with depending arms 32. These arms have at the lower ends thereof rollers 33 and the latter coact with angularly disposed cam blocks 34 in such manner that at 55 the end of the retractile stroke or shift of the grippers the upper members of the grippers are swung or tilted into released position with respect to the applicator. The cam blocks 34 are mounted on the base plate 10 and are positioned or disposed, as shown in Figure 2. A stop 35 on one of the rods 29 operates to limit movement of the grippers in the direction of the knife. In carrying out the improved method the grippers are shifted to their fullest extent away from the knife 60 65 70 75 80 85 90 95 100 105 110 115 120 125 130 135 140 145 150 155 160 165 170 175 180 185 the upper members of the grippers are swung into gripping relation with the side portions of the applicator due to the action of the springs 28 and the fact that the rollers 33 leave the cam blocks 34. During continuation of shift of the grippers in the direction of the knife the grippers move apart and effect stretching of the applicator. When the grippers reach the end of their forward stroke they present the applicator 10 in a fully stretched condition to the knife. In connection with completion of their forward stroke they bring the stretched portion of the applicator into contact with the knife and the latter effects or serves to form a circular slit in 15 and beyond the stretched portion of the applicator. After slitting of the applicator by the knife the grippers and support are shifted away from the knife. During the retractile movement the grippers move toward one another and hence 20 release the applicator from its stretched condition. As the grippers reach the end of their retractile movement the upper members are released from their clamped position with respect to the applicator due to the action of the rollers 25 33 and the cam block 34.

As shown in Figure 4, the grippers grip the applicator at points only when they are shifted fully forwards so as to bring the knife into cutting engagement with the stretched portion and 30 the knife penetrates through and beyond the stretched portion. As a result of this when the applicator is released the slit has the contour shown by dotted lines in Figure 6 and embodies the restricted entrance 9.

35 This application is a division of patent application, Serial No. 301,343, filed by me on October 26, 1939 (now Patent No. 2,213,721, dated September 3, 1940).

The herein described method results in the 40 formation in the applicator of a pocket forming slit with a restricted entrance. It is essentially a simple one and may be carried out expeditiously.

The invention is not to be understood as 45 restricted to the details set forth since these may be modified within the scope of the appended claims without departing from the spirit and scope of the invention.

Having thus described the invention what I 50 claim as new and desire to secure by Letters Patent is:

1. The method of forming in an elastic porous pad-like applicator a pocket with a restricted entrance, which comprises first stretching one 55 side portion of the applicator, then while said portion is stretched slitting the applicator through and beyond said portion, and finally releasing the applicator so that it assumes its normal shape.

2. The method of forming in an elastic porous pad-like applicator a pocket with a restricted entrance, which comprises first stretching one side portion of the applicator, then while said 60 portion is stretched forming in and beyond said portion a semi-circular slit, and finally releasing the applicator so that it assumes its normal shape.

3. The method of forming in an elastic porous pad-like applicator a pocket with a restricted entrance, which comprises gripping the applicator at two marginal points at one side of the center, then stretching said portion of the applicator 5 therebetween, then while the portion is stretched slitting the applicator through and beyond said portion, and finally releasing the applicator so that it assumes its normal shape.

4. The method of forming in an elastic porous 10 pad-like applicator a pocket with a restricted entrance, which comprises moistening the applicator, then stretching one side portion of said applicator, then while the portion is stretched slitting the applicator through and beyond said 15 portion, and finally releasing the applicator so that it assumes its normal shape.

5. The method of forming in an elastic porous 20 pad-like applicator a pocket with a restricted entrance, which comprises first moistening the applicator, then stretching one side portion thereof, then while the portion is stretched forming in and beyond said portion a substantially semi-circular slit, and then releasing the applicator so that it assumes its normal shape.

6. The method of forming in an elastic porous 25 pad-like applicator a pocket with a restricted entrance, which comprises stretching one side portion of the applicator, then while the portion is stretched slitting the applicator by inserting a 30 knife through said portion and into another portion of the applicator, then withdrawing the knife, and finally releasing the applicator so that it assumes its normal shape.

7. The method of forming in an elastic porous 35 pad-like applicator a pocket with a restricted entrance, which comprises moistening the applicator, then gripping the applicator at two marginal points at one side of the center, then stretching the portion of the applicator between 40 said points, then while the portion is stretched slitting the applicator by inserting a knife through said portion and into another portion of the application, then withdrawing the knife, and finally releasing the applicator so that it assumes 45 its normal shape.

8. The method of forming in an elastic porous disc-like applicator a pocket with a restricted peripheral entrance, which comprises gripping the applicator at the ends of a cordal line substantially midway between the periphery and the 50 ends of the applicator, then stretching the applicator between the gripped parts until the peripheral portion therebetween is substantially straight, then slitting the applicator by inserting a knife through the stretched peripheral portion and into other portions of the applicator, then withdrawing the knife, and finally releasing the applicator so that it assumes its normal shape.

9. That improvement which comprises stretching one side portion of an elastic pad-like applicator, then slitting the stretched portion of the applicator, and finally releasing the applicator so that it assumes its normal shape.

JOHN F. SKOLD.
